UNITED STATES PATENT OFFICE

98,953

DESIGN FOR A SHOE

Meyer Margolin, Elgin, Ill.

Application January 21, 1936, Serial No. 60,701

Term of patent 3½ years

To all whom it may concern:

Be it known that I, Meyer Margolin, a citizen of the United States of America, residing in Elgin, county of Kane, and State of Illinois, have invented a new, original, and ornamental Design for a Shoe, of which the following is a specification, reference being had to the accompanying drawing, forming part thereof, wherein,

I claim:

The ornamental design for a shoe, substantially as shown.

MEYER MARGOLIN.
